(57) **CLAIM**

We claim the ornamental design for a robotic arm, as shown and described.

DESCRIPTION

FIG. 1 is a first isometric view of a robotic arm in accordance with the present disclosure;

FIG. 2 is a first side view of the robotic arm of FIG. 1;

FIG. 3 is a second side view of the robotic arm of FIG. 1;

FIG. 4 is a front view of the robotic arm of FIG. 1;

FIG. 5 is a rear view of the robotic arm of FIG. 1;

FIG. 6 is a top view of the robotic arm of FIG. 1;

FIG. 7 is a bottom view of the robotic arm of FIG. 1; and,

FIG. 8 is a second isometric view of the robotic arm of FIG. 1.

The broken lines in the drawings depict portions of the robotic arm which form no part of the claimed design.
